TELEPHONE EARPIECE

Erich Hausdorf, Berlin, Germany

Application August 19, 1935, Serial No. 36,915
In Germany April 9, 1935

8 Claims. (Cl. 179—182)

The invention relates to a telephone earpiece, which comprises a cap adapted to be placed against the ear and surround the same, and a dome-like portion which contains the electrical apparatus and is adapted to engage into the ear.

The object of the invention is to provide for greater intelligibility and increased intensity of sound in connection with earpieces of this description.

10 This is accomplished according to the invention by the fact that the dome-like portion is subdivided by ribs which are disposed vertically to the base thereof. These ribs in the dome-like portion are crossed or arranged radially, and terminate in a sound outlet aperture in the wall of the dome.

In earpieces of the kind in question the intelligibility is also affected detrimentally by the so-called cap effect. According to the invention, 20 this disadvantage is overcome by the fact that the surfaces, which serve to confine the space between the portion of the earpiece surrounding the ear and that engaging into the ear, and which heretofore have been perfectly smooth, are made irregular. These surfaces are furnished with ribs or the like. In addition they may be hammered or punched.

25 Earpieces are frequently made of resinous or other non-metallic materials which are pressed into form. Now it has been found that owing to fluctuations in the temperature, varying humidity or also by reason of concussions or vibrations the threaded connection which is employed for tensioning the diaphragm within the earpiece is caused to become loose.

30 This loosening action also tends to diminish considerably the intelligibility. To avoid this drawback the cross-section of the thread serving for connection of the parts and the tensioning of 40 the diaphragm is made in the form of a right-angled triangle, the hypotenuse of which is directed towards the diaphragm.

The invention is illustrated by way of example in the accompanying drawing, in which

45 Fig. 1 is a longitudinal section through an earpiece according to the invention.

Fig. 2 shows a portion of the earpiece according to Fig. 1 on enlarged scale. This figure illustrates more particularly the thread employed for 50 connecting the parts.

Fig. 3 is a front view of the earpiece according to Fig. 1.

Referring now to the drawing, 1 is the cap which is adapted to be placed against the ear. 55 The part 2 of the earpiece is connected with the

part 1 in suitable fashion. This portion 2 passes over into the dome 3.

The dome possesses the sound outlet apertures 4. According to the invention, the space 5a of the dome is subdivided by a plurality of ribs 5. In 5 the particular form of embodiment shown there are thus produced four equal compartments. The ribs 5 taper off towards the bottom 7 of the dome and, as shown in Fig. 3, may be allowed to intersect. The central point 8 of the intersecting ribs 10 coincides with the central axis of the earpiece.

Since the ribs 5 are tapered off towards the bottom of the dome the compartments converge toward the sound outlet and thereby effect an intensification of the sound waves. 15

The undesirable cap effect results in the space between the ear, the surrounding portion 1, the part 2 and the dome 3. In the form of embodiment illustrated in the drawing there are disposed between the part 2 and the lower portion of 20 the dome ribs 6. In addition the surfaces between the ribs are made to be irregular, for example by being hammered or otherwise roughened or indented, as indicated at 6a. The surface of the dome itself will preferably not be treated in 25 this fashion. On the other hand the surfaces adjacent the dome and the inner surfaces of the cap 1 surrounding the ear will again be irregular, for example hammered. This treatment of the 30 surfaces resting against the ear also results in the fact that the said surfaces do not press unduly on the ear, which is frequently a source of inconvenience at the present time in the case of lengthy conversations. It has also been found that the 35 roughened surface against the ear assists towards a facilitated application of the earpiece to the ear.

11 is the part of the earpiece containing the magnet system acting on the diaphragm. This part 11, as shown in Figs. 1 and 2, is secured to the 40 part 2 by means of a thread. The part 2 possesses an annulus 10. Between the end of the casing 11 and the annulus 10 there is tensioned the diaphragm 9. The thread employed for connecting the parts is illustrated on enlarged scale in Fig. 2. 45 As shown in the drawing, the cross-section of the thread constitutes a right-angled triangle, the hypotenuse 12 of which is directed towards the diaphragm, resulting in the advantages previously referred to. 50

What I claim as new and desire to secure by Letters Patent is:

1. A telephone earpiece comprising in combination, a cap adapted to fit against the ear and surround the same, a dome-like portion adapted to 55

engage into the ear, and ribs in the said dome-like portion disposed angularly to the base of the dome and dividing the said dome-like portion into single compartments, all of said compartments converging toward the sound outlets whereby the sound is intensified at these outlets.

5 2. A telephone earpiece comprising in combination, a cap adapted to fit against the ear and surround the same, a dome-like portion 10 adapted to engage into the ear, and radially disposed ribs in the said dome-like portion dividing it into single compartments, all of said compartments converging toward the sound outlets whereby the sound is intensified at these outlets.

15 3. A telephone earpiece comprising in combination, a cap adapted to fit against the ear and surround the same, a dome-like portion adapted to engage into the ear, and intersecting ribs in the dome-like portion dividing it into single compartments, all of said compartments converging toward the sound outlets whereby the sound is intensified at these outlets.

20 4. A telephone earpiece comprising in combination, a cap adapted to fit against the ear and 25 surround the same, a dome-like portion adapted to engage into the ear, and ribs in the said dome-like portion dividing it into single compartments and terminating in sound outlets in the wall of the dome, all of said compartments converging 30 toward the sound outlets whereby the sound is intensified at these outlets.

25 5. A telephone earpiece comprising in combination, a cap adapted to fit against the ear and surround the same, a dome-like portion adapted 30 to engage into the ear, and ribs in the said

dome-like portion dividing it into single compartments, said ribs being tapered towards the base of the dome whereby all of the compartments converge toward the sound outlet so that the sound is intensified at these outlets.

5 6. A telephone earpiece comprising in combination, a cap adapted to fit against the ear and surround the same, a dome-like portion adapted to engage into the ear, and intersecting ribs in the said dome-like portion dividing it 10 into single compartments, the central point of the said ribs coinciding with the central axis of the earpiece, all of said compartments converging toward the sound outlets whereby the sound is intensified at these outlets.

15 7. In a telephone earpiece, a cap adapted to fit against the ear and surround the same, a dome-like portion adapted to engage into the ear, and ribs in the said dome-like portion dividing it into single compartments, the surfaces in 20 the space between the said cap and the said dome-like portion being roughened to break the sounds, all of said compartments converging toward the sound outlets whereby the sound is intensified at these outlets.

25 8. In a telephone earpiece, a cap adapted to fit against the ear and surround the same, a dome-like portion adapted to engage into the ear, ribs in the said dome-like portion dividing it into single compartments, and ribs in the space 30 between the said cap and the said dome-like portion all of said compartments converging toward the sound outlets whereby the sound is intensified at these outlets.
